UNITED STATES PATENT OFFICE.

ALBÉRIC LOUIS CHOPIN, OF PARIS, FRANCE.

PERCUSSION-DRILL.

1,330,170.

Specification of Letters Patent. Patented Feb. 10, 1920.

Application filed January 26, 1917. Serial No. 144,783.

To all whom it may concern:

Be it known that I, ALBÉRIC LOUIS CHOPIN, residing at Paris, France, have invented new and useful Improvements in or Relating to 5 Percussion-Drills, of which the following is a specification.

This invention relates to improvements in drills, particularly to that class of drills operated by compressed air or hydraulically, 10 one object of the invention being to effect improvements in the construction of the cover of the body of the drill by providing said cover with a handle projecting therefrom at right angles to the axis of the body and 15 forming the air inlet duct, and by also providing said handle with inlet controlling means.

Another object of the invention is to effect improvements in the construction of the 20 drill by providing removable cover and tool guiding sleeve for the opposite ends of the drill body, and by also providing a ring to bear against the outer side of said sleeve and common securing means for said ring and 25 the cover, said common securing means being quickly detachable from the ring and cover, to enable the drill to be readily disassembled and to facilitate repair.

With the above and other objects in view, 30 the invention consists in the construction, combination and arrangement of devices hereinafter described and claimed.

Figure 1 is an elevation of a drill constructed and arranged in accordance with 35 my invention.

Fig. 2 is a detail sectional view of the same, and showing the construction of the cover and of the upper or inner end of the securing rod.

Fig. 3 is a similar view, showing the outer portion of the drill.

Fig. 4 is a transverse sectional view of the same on the plane indicated by the line 4—4 of Fig. 3.

Fig. 5 is a similar view on the plane indicated by the line 5—5 of Fig. 3.

Fig. 6 is a detail elevation of one of the securing rods.

Fig. 7 is a detail elevation of the drill, 50 showing the lugs of the ring in section and disclosing the engagement of one of the securing rods with such lugs.

The body 3 of my improved drill is of the usual cylindrical form, is open at the opposite ends, and is inclosed in a casing 21. A 55 chamber 22 is formed between the casing

and the body and the casing is provided with exhaust openings 23 through which the exhaust air escapes. This causes the dust to be discharged at a point of the drill 60 where the dust is the least injurious to the operator. The cover 1 which closes the inner end of the body is provided with a handle 2 which projects therefrom at right angles to the axis of the body, said handle 65 being provided with a bore which forms the air inlet duct, and being also provided with inlet controlling means 2^a. Dowel pins 13 connect the cover to the body and the cover is provided preferably with a screw threaded boss 29' to enable a pneumatic thrust cylinder E of usual construction to be secured thereto, as indicated in dotted lines in Fig. 1. The cover is also provided, on opposite sides, with pairs of spaced lugs 5 70 which project outwardly therefrom and each of the said lugs has a recess in its upper side as shown in Fig. 2.

A sleeve 9 is detachably fitted in the outer end of the body 3 and is provided with an annular flange which bears against said end of the wall of the body. Said sleeve receives the inner end of the tool 10. The inner portion of the tool also extends through a ring 7 which is arranged at the 80 outer end of the sleeve 9, a gasket 8 being fitted between said ring and said sleeve, as shown in Fig. 3. The said ring is provided on opposite sides with pairs of spaced lugs 7' 85 which project outwardly therefrom.

Common securing rods 4 are provided for the cover and ring. The outer ends of the securing rods are arranged in the spaces between the lugs 7' of the ring and are formed with T-heads 4^a which bear against the outer sides of said lugs, as shown in Fig. 3 and in detail in Fig. 5. The inner ends of the said rods are detachably fitted between the lugs 5 of the cover and are each provided with an opening, and cotters 6 are inserted in said 90 openings and bear in the recesses of the lugs 5 of the cover. The rods and cotters coact with the lugs of the cover and ring to securely hold the cover and ring in place. By first removing the cotters the rods can be 100 readily detached from the lugs of the cover and ring to permit the cover and ring to be removed when this is desired. Hence the parts of the drill can be readily disassembled.

A collar 14 which is more fully described in my copending application for Letters

Patent of the United States, Serial No. 224,620, filed March 25, 1918, is arranged around the tool and is provided on opposite sides with lugs 15 and bosses 16. Links 17, 18, which are also more particularly described in my said copending application, are connected respectively to the lugs 15, bosses 16, and to the lugs 7^a of the ring, the said links forming securing means for the 10 said collar and being independent of the rod 4 which forms the common securing means of the cover and ring.

I claim as my invention:—

In a percussion drill of the class described, 15 a cylinder body, a cover for one end of the body, a tool guiding sleeve in the other end of the body and having a flange bearing against the end of the wall thereof, a ring

on the outer end of the sleeve, the said ring and the said cover being each provided with 20 pairs of spaced lugs projecting outwardly therefrom, rods having T-heads at one end detachably fitted between and engaging the lugs of the ring, the other ends of the rods being detachably fitted between the lugs of 25 the cover and being provided with transverse openings, and fastening means in said openings and bearing on the lugs of the cover.

In testimony whereof I affix my signature 30 in presence of two witnesses.

ALBÉRIC LOUIS CHOPIN. [L. S.]

Witnesses:
